ELECTROSURGICAL RESECTING
INSTRUMENT

Frederick J. Wallace, New York, N. Y., assignor to
American Cystoscope Makers, Inc., New York,
N. Y., a corporation of New York

Application July 10, 1945, Serial No. 604,220

9 Claims. (Cl. 128—303.15)

1

This invention relates to a surgical instrument, and more particularly to such an instrument adapted, among other things, to remove protrusions, tissue growths and the like by resection with the aid of a high frequency electric current.

The instrument of this invention has wide application in the field of surgery and is capable of readily resecting protrusions on the exterior of a body and protrusions, tumorous growths or other masses of body tissue in body passages and cavities. For example, the present invention may be readily employed for the resection of protrusions in the urethra and bladder neck, and for the excision of undesirable growths on the prostate gland and other internal organs.

As will be apparent to a person skilled in the art from the detailed description that follows, the instrument may be inserted in a body passage or cavity to the region of the protrusion or the like which is to be removed, whereupon the protrusion or the like may be resected by a high frequency cutting electrode under conditions of illuminated vision. One of the features of the invention resides in the provision of a cutting electrode that is adapted to be rotated continuously and automatically, to the end that the protrusion or tissue growth may be quickly and readily resected with a minimum of effort and strain on the surgeon operating the instrument, and with corresponding reduction in discomfort and in general physical and nervous effect on the patient.

In present day high frequency electrosurgical instruments, the cutting electrodes have to be manually actuated by the surgeon to cut away a piece of a protrusion at a time. This procedure involves the cutting off of a relatively small portion of the protrusion with each manual actuation of the cutting electrode. This is objectionable for several reasons. First, the resection or excision of a large mass of tissue by taking small individual cuts is a tedious and timely operation. Also, a surgeon performing the resection in this manner is under considerable physical strain and nervous tension as he is obliged to manually actuate the electrode for each individual cut in pruning away a mass of tissue. Moreover, the patient may also be under considerable strain during the operation, and is quite often subjected to pain and discomfort due to the presence of the instrument in his body and as a consequence of the operation of the instrument.

The present invention eliminates these objections as it contemplates the employment of an electrode having a configuration and so arranged

2

as to be continuously operated at the will of the surgeon and expeditiously resect protrusions without undue discomfort to the patient and with a diminution of effort and strain on the part of the surgeon. The instrument may include an endoscopic tube having a lateral fenestra and provided with a removable telescope having a source of illumination opposite the fenestra. A rotary shaft is mounted in the endoscopic tube and has secured thereto a cutting electrode, disposed in the region of the fenestra and rotatable with the shaft. One preferred form of cutting electrode is substantially helical in configuration and attains a screw-like movement in the course of its actuation by the rotary shaft. The endoscopic tube, telescope, and rotary shaft are mounted at their rearward ends on a supporting device having a hollow handle in the form of a pistol grip. Preferably within the supporting device is a prime mover and cooperating speed-reducing gearing for imparting continuous rotation to the rotary shaft and the electrode. The prime mover may comprise a suitable small electric motor or fluid actuated unit, as desired. Provision is made in the instrument for transmitting and/or withdrawing fluid through the instrument into and from a body cavity. The various parts may be readily assembled into the unitary structure and dismantled for repair and other purposes, as will be apparent from the detailed description that follows.

It is the primary object of this invention to provide a surgical instrument for more readily and expeditiously resecting a protrusion or the like than has been possible heretofore.

This invention has for another object the provision of a high frequency electrosurgical instrument wherein the cutting electrode may be actuated continuously at the will of the operator.

It is another object of the invention to provide an instrument of the character indicated, including a rotary cutting electrode that is adapted to be continuously operated through the medium of a driving unit, such as an electric motor or a fluid actuated prime mover.

A further object of the invention is to provide an electrosurgical instrument of the character described that is relatively simple and compact in design, reasonable in manufacturing and upkeep costs, and capable of performing its intended functions in an effective and trouble-free manner.

These objects, as well as other objects, together with the advantages obtainable by the practice of this invention, will be readily apparent to per-

sons skilled in the art by reference to the following detailed description taken in conjunction with the annexed drawings which respectively describe and illustrate preferred embodiments of the invention.

In the drawings:

Figure 1 is a side elevational view of an instrument embodying the devices of the invention, partly in vertical cross section and with parts broken away for better illustration;

Figure 2 is a cross-sectional view taken along line 2—2 of Figure 1;

Figure 3 is a cross-sectional view taken along line 3—3 of Figure 1;

Figure 4 is an enlarged cross-sectional view taken along line 4—4 of Figure 1;

Figure 5 is an enlarged cross-sectional view taken along line 5—5 of Figure 1;

Figure 6 is an enlarged perspective view of a device employed with this invention;

Figure 7 is an enlarged view, partly in vertical cross section, of the cutting electrode and associated devices shown in Figure 1;

Figures 8—11, inclusive, are views similar to Figure 7 and illustrating modifications of the cutting electrode.

Referring now to the drawings wherein like reference characters denote corresponding parts throughout the several views, and more particularly to Figure 1, there is shown an outer endoscopic tubular member 15 provided at its forward end with a curved beak or nosepiece 16, having an aperture 17 that is substantially parallel with the axis of the tubular member, and provided with a lateral fenestra 18. The rearward end of tubular member 15 is preferably threaded externally for engagement with corresponding internal threads in a flared collar 19 to form an effective fluid-tight connection therewith. The rearward end of collar 19 is provided with a forwardly and inwardly tapered recess 20 and a passage 21 in fluid communication with the interior of tubular member 15 and a conduit 22.

In Figure 6 there is depicted in enlargement a device 23 that is adapted to be inserted into and removed from tubular member 15 at will. Device 23 includes a unitary bundle of tubes 24, 25, 26 and 27, tube 24 being adapted to accommodate a telescope, tubes 25 and 26 being adapted to respectively introduce and withdraw an irrigating fluid through the instrument, and tube 27, having a longitudinal slot 28, being adapted to support an electrode shaft, all as more fully described further along herein. A depending support 29 is spaced from the forward end of tubes 25, 26 and 27, forming an opening 30 therebetween and having an aperture 31 that is axially coincident with tube 27 and aperture 17 when the parts are in assembled relation, as shown in Figure 1. Secured in sealed relation to the rearward end portion of the bundle of tubes is a frusto conical collar 32 adapted to be received in recess 20 and form a snug fluid-tight connection with collar 19. Collar 32 carries a flange 33 having a series of circumferentially spaced tapped openings 34, 35 and 36. As will be observed in Figure 3, tapped openings 35 are provided with petcocks 37 and 38, that respectively communicate through ducts 39 and 40 with corresponding tubes 25 and 26.

Collar 32 and associated parts are mounted on a supporting device that will now be described, and that includes a hollow handle 45 of the pistol grip type having a top wall 46. The upper forward portion of wall 46 is in the nature of a

saddle 47 wherein flange 33 of collar 32 is seated and is attached by set screws 48 that engage with tapped openings 36 (Figure 3). A bore 49, closed at its rearward end by a screw plug 50, constitutes a compartment within which a prime mover, hereinafter described, is housed. Directly above this compartment is a block of insulating material 51 that may be composed of hard rubber. A bridge 52 is attached to block 51 by set screws 53 and to flange 33 of collar 32 by set screws 54. The forward end portion 55 of the bridge is bifurcated longitudinally to receive a post 56 that projects upwardly of collar 19. Post 56 carries a locking attachment 57 for effecting coupling engagement between the post and bridge 52. Preferably integral with bridge 52 at its rearward end is a depending arm 58 having a first opening 59 coaxial with a bore 60 in block 51 and with tube 24, and a relatively smaller second opening 61 that is parallel with opening 59.

A telescope, generally indicated by reference numeral 65, includes a tubular body 66 of relatively small diameter adapted to be inserted through opening 59, bore 60 and tube 24 so that an electric lamp 67 at its forward end may be positioned opposite fenestra 18 for providing illumination therethrough. The telescope is preferably constructed with a portion of enlarged diameter 68 that forms a snug frictional fit with opening 59 in arm 58 and carries an aligning pin 69 that registers with opening 61. At the rearward end of the telescope is an eyepiece 70. The telescope lens system (not shown) may be of any suitable type, such as, for example, the lens system disclosed in the patent to R. H. Wappler 1,680,490, granted August 14, 1928. The telescope is provided with the usual terminal members 71, electrical plug 72 for connection to a convenient source of electricity (not shown), and a pair of contact arms 73.

A rotary hollow shaft 75 is disposed within tube 27. Coaxially arranged within and spaced from the inner surface of hollow shaft 75 by a sheath of insulating material 76 is an electrically conductive rod 77. As will be noted from an examination of Figures 1 and 7, both end portions of rod 77 extend beyond the confines of hollow shaft 75, the rearward end portion of the rod being free of the insulating material.

A preferred form of the cutting electrode is shown in Figures 1, 5 and 7 and consists of a pair of electrically conductive wires 78, each of which is bent intermediate its ends to assume the generally helical illustrated configuration. The rearward end of each wire 78 is imbedded in the forward end portion of rod 77, while the forward end of each of these wires is imbedded in a shaft-like element of electrical insulating material 79 that is accommodated in aperture 31 of support 29 and aperture 17 of beak 16 for rotation therein when the parts are in assembled relation, as shown in Figure 1. A collar 80 is mounted on rod 77 and is spaced rearwardly of hollow shaft 75 and insulating sheath 76. The extreme end portion 81 of rod 77 extends into an electrically conductive bearing 82 that is maintained in a cavity in block 51 by a screw plug 83 of electrical insulating material. Rod portion 81 is in close contact with block 82, which, in turn, is in electrical communication with an electrode terminal 84 that is adapted to be connected with a suitable source of high frequency electric current (not shown).

As is best shown in Figure 1, one end face of

collar 80 bears against bushing 82 to restrain rod 77 and hollow shaft 75 against rearward movement. Rod 77 and hollow shaft 75 are restrained against forward movement through the aid of a detent means that will now be described, having particular reference to Figures 1 and 2. This includes a hollow plug 85 threadedly mounted in one side of block 54 and having a pin or detent 86 reciprocable therein and extending therethrough. Detent 86 carries a flange 87 and is normally and yieldingly urged toward the right, as viewed in Figure 2, through the coaction of flange 87 and a coaxial compression spring 88; to the end that an extremity of detent 86 is received in an opening 89 in the block. The outer end of detent 86 carries a knob 90 for manually moving the detent toward the left, as viewed in Figure 2, against the action of compression spring 88. It will be observed that detent 86, when in protracted position, extends beneath rod 77 and bears against the forward end face of collar 80 to thereby restrain rod 77 and shaft 75 against forward movement.

Continuous rotation is imparted to hollow shaft 75 and thence to the cutting electrode through the medium of driving devices shown in Figure 1. These devices preferably include a prime mover or motor, denoted by reference character P, that is housed within compartment 49. The prime mover may be either an electric motor or a fluid actuated unit of suitable size and having requisite characteristics. A conduit 92 extending through the interior of hollow handle 45 connects at its upper end with prime mover P and at its lower end with a coupling element 93 in the bottom wall of the handle. If the prime mover is an electric motor, a cable having electric conductors is passed upwardly through conduit 92 to the motor and is connected to an appropriate source of electrical supply for energizing the motor. Should prime mover P be a fluid actuated unit, the actuating fluid is transmitted from a convenient source (not shown) to coupling element 93 through conduit 92, and thence to the unit. The prime mover may be placed in and out of service by a suitable foot-operated control (not shown) in order that the surgeon's hands may be free to handle the instrument and perform the operation. Integral with prime mover P is a speed-reducing device R that may consist of an appropriate train of gears and that has an aligning pin 94 registering with a blind bore 95 in wall 46. Actuation of prime mover P and speed-reducing device R imparts rotation to a drive gear 96 that meshes with an idler gear 97 which in turn engages a gear 98 formed in the rear end of hollow shaft 75, whereby continuous rotation is imparted to cutting electrode 78.

The cutting electrode illustrated in Figure 8 consists essentially of a central longitudinal portion that is parallel with the axis of hollow shaft 75, a forward crank portion 101 that is imbedded in shaftlike element 79 and a rearward crank portion 102 that is imbedded in rod 77.

In Figures 9, 10 and 11, there are illustrated three helical cutting electrode arrangements. Referring first to Figure 9, the cutting electrode shown therein is in the form of a helical wire interposed between and imbedded at its opposite ends in element 79 and rod 77, respectively.

The helical wire cutting electrode 104 of Figure 10 is coaxial and rotatable with a member 105 that constitutes an extension of rod 77, and that is welded or otherwise secured to the end portions 75

105 and 107 of the cutting electrode. It will be noted that with this type of construction, the forward end of member 105 is imbedded in element 79.

5 The cutting electrode arrangement shown in Figure 11 contemplates a transparent core member 108 made of an electrical insulating material, such as glass, and having a rounded forward end portion 109 adapted to be rotatably positioned in aperture 31 of depending member 29 and aperture 17 in the curved beak. The rearward end portion 110 is recessed to non-rotatably engage the forward end of rod 77. Core member 108 is fashioned with an inner helical groove 111 and a 15 second helical groove 112, the latter carrying a helical cutting electrode wire 113 that has its rearward end portion 114 arranged in electrical contact with rod 77.

For the purpose of briefly outlining the operation of the instrument of this invention, let us 20 assume that it is to be used for the resection of a prostate growth. The parts within endoscopic tubular member 15 are removed and an obturator is placed therein. The tubular member 15 is 25 then inserted, beak end first, through the urethra until fenestra 18 arrives at the proximate location of the prostate growth. The body fluids are withdrawn through the sheath and conduit 22 and the obturator is withdrawn. The various other 30 devices are then assembled in the relative positions shown in Figure 1. Electrical connection with lamp 67 of telescope 65 is made through plug 71. Electrode terminal 84 is connected with one terminal of the source of high frequency 35 electric current, the patient being grounded or suitably connected with the other terminal of the high frequency current source. An irrigating liquid may be transmitted through petcock 31, duct 39 and tube 25 and withdrawn through tube 26, passage 40 and the other petcock 31. The surgeon grips handle 45 in one hand and sights 40 through the telescope to locate the exact region where it is desired to carry out the cutting operation. He may manipulate the instrument to bring 45 it to the proper region within the body. The growth that is to be cut is accommodated within fenestra 18, the high frequency circuit is completed, and the prime mover is placed in service. At such time, the prime mover P, cooperating with 50 speed reducer R, imparts rotation to hollow shaft 75 and thence to cutting electrode 78 through meshing gears 96, 97 and 98. It will be readily apparent to persons skilled in the art that the 55 instrument of this invention is so constructed and arranged as to facilitate and expedite the resection of the growth.

From the foregoing, it is believed that the construction, operation and advantages of my present invention will be readily comprehended by 60 persons skilled in the art. It is to be clearly understood, however, that various changes in the apparatus may be resorted to without departing from the spirit of the invention, as defined by the appended claims.

65 I claim:

1. In a surgical instrument of the character described, a tubular member having a fenestra formed therein, at least one electrode wire rotatably supported within the tubular member and positioned at least in part within the fenestra, a portion of the electrode wire intermediate its ends being substantially helical in configuration, and means comprising a motor for imparting continuous rotation to the electrode wire.

2. In a surgical instrument of the character

described, a tubular member having a fenestra formed therein, a rotary shaft disposed in the tubular member, a substantially helical cutting electrode positioned at least in part within the fenestra, said cutting electrode being substantially coaxial with the shaft and having one end secured thereto for rotation therewith, and means comprising a motor for imparting continuous rotation to the shaft.

3. In a surgical instrument of the character described, a tubular member having a fenestra formed therein, a rotary shaft disposed in the tubular member, a substantially helical cutting electrode positioned at least in part within the fenestra, said cutting electrode being substantially coaxial with the shaft and having its end portions affixed to the shaft for rotation therewith, and means comprising a motor for imparting continuous rotation to the shaft.

4. In a surgical instrument of the character described, a tubular member having a fenestra formed therein, a rotary shaft disposed in the tubular member, a transparent electrically non-conductive element substantially coaxial with the shaft and rotatable therewith, said element carrying a substantially helical cutting electrode positioned at least in part within the fenestra, and means comprising a motor for imparting continuous rotation to the shaft.

5. In a surgical instrument of the character described, a tubular member having a lateral fenestra, a supporting device removably secured to the tubular member, a rotary shaft journaled in the tubular member and the supporting device, a cutting electrode positioned at least in part within the fenestra and connected to the shaft for rotation therewith, means including an electric motor carried by the supporting device for imparting continuous rotation to the shaft, and means comprising a spring pressed detent for maintaining the shaft in operative engagement with the last mentioned means.

6. In a surgical instrument of the character described, a tubular member having a lateral fenestra, a supporting device removably secured to the tubular member, a rotary shaft journaled in the tubular member and the supporting device, a cutting electrode positioned at least in part within the fenestra and connected to the shaft for rotation therewith, means including a fluid actuated motor carried by the supporting device for imparting continuous rotation to the shaft, and means comprising a spring pressed detent for maintaining the shaft in operative engagement with the last mentioned means.

7. In a surgical instrument of the character described, a tubular member having a lateral fenestra, a hollow supporting device removably

secured to the tubular member, a rotary shaft journaled in the tubular member and the supporting device, a substantially helical cutting electrode positioned at least in part within the fenestra, said cutting electrode being substantially coaxial with the shaft and having one end secured thereto for rotation therewith, an electric motor mounted in the hollow supporting device for imparting continuous rotation to the shaft and means comprising a detent for maintaining the shaft in operative engagement with the electric motor.

5 8. In a surgical instrument of the character described, a tubular member having a lateral fenestra, a hollow supporting device removably secured to the tubular member, a rotary shaft journaled in the tubular member and the supporting device, a substantially helical cutting electrode positioned at least in part within the fenestra, said cutting electrode being substantially coaxial with the shaft and having its end portions affixed to the shaft for rotation therewith, an electric motor mounted in the hollow supporting device for imparting continuous rotation to the shaft and means comprising a detent for maintaining the shaft in operative engagement with the electric motor.

15 9. In a surgical instrument of the character described, a tubular member having a lateral fenestra, a hollow supporting device removably secured to the tubular member, a rotary shaft journaled in the tubular member and the supporting device, a transparent electrically non-conductive element substantially coaxial with the shaft and rotatable therewith, said element carrying a substantially helical cutting electrode positioned at least in part within the fenestra, an electric motor mounted in the hollow supporting device for imparting continuous rotation to the shaft and means comprising a detent for maintaining the shaft in operative engagement with the electric motor.

20 10. In a surgical instrument of the character described, a tubular member having a lateral fenestra, a hollow supporting device removably secured to the tubular member, a rotary shaft journaled in the tubular member and the supporting device, a transparent electrically non-conductive element substantially coaxial with the shaft and rotatable therewith, said element carrying a substantially helical cutting electrode positioned at least in part within the fenestra, an electric motor mounted in the hollow supporting device for imparting continuous rotation to the shaft and means comprising a detent for maintaining the shaft in operative engagement with the electric motor.
